UNITED STATES PATENT OFFICE.

WILLIAM M. TAYLOR, OF STEPHENVILLE, TEXAS.

HEADING-MACHINE.

No. 902,928.

Specification of Letters Patent.

Patented Nov. 3, 1908.

Application filed November 7, 1906. Serial No. 342,417.

To all whom it may concern:

Be it known that I, WILLIAM M. TAYLOR, a citizen of the United States, residing at Stephenville, county of Erath, and State of Texas, have invented certain new and useful Improvements in Heading-Machines, of which the following is a specification.

My invention relates to machines for cutting the heads of cane sorghum, Kafir corn, 10 and millo maize, and like plants and for gathering the heads as they are cut, and the object is to provide a machine for cutting the heads from cane of any ordinary height, to provide such machine with means for 15 shifting the cane-heads into position to be cut by blades carried by the machine, and to provide means for collecting the heads as they are cut from the stalks. Other objects and advantages will be fully understood 20 from the following description and the invention will be more particularly pointed out in the claims.

Reference is had to the accompanying drawings which form a part of this application 25 and specification.

Figure 1 is a plan view of the machine provided with an elevator for carrying the heads to a wagon. Fig. 2 is a front elevation of the machine, the tongue being left off 30 and showing a dumping box instead of the elevator shown in Fig. 1. Fig. 3 is a side elevation of the invention omitting the tongue. Fig. 4 is a broken detail view illustrating the manner of throwing the machine 35 out of gear with the power shaft. Fig. 5 is a plan view of the knives, showing their relative position to each other. Fig. 6 is a detail view, illustrating the gearing at one corner of the elevating mechanism. Fig. 7 is a 40 plan view of one of the frame pieces or sills for supporting the head cutting and gathering mechanism. Fig. 8 is a detail view of the clutch operating lever. Fig. 9 is a 45 broken rear elevation of the gear for the cutting mechanism, the view being on an enlarged scale. Fig. 10 is a side elevation of the lower bearing shown in Fig. 9.

Similar characters of reference are used 50 to indicate the same parts throughout the several views.

The frame portions of this machine are 55 preferably constructed of pipe. The sills 1 and 2 are supported at their rear ends on the axle 3 and the front ends are supported on the wheels 4 by means of forks 5. The forward portions 6 are supported in T-connec-

tions 7 into which the shanks of the forks 5 are screwed. For a front frame piece an arch 8, is used instead of a straight axle because the arch will not bend the plants down and the 60 arch is made high enough to pass over all ordinary plants. Guides 10 answer somewhat as a tongue for the machine, but they do more. The guides are flared at the front and serve to gather the cane and bring it 65 closer together. An arch 11 connects the front ends of the guides 10 and arms 12 are attached to the ends of the arch and project down and outward for straightening up stalks of cane that may be bent over. In 70 this manner heads are saved that would be lost without these arms. The machine is not drawn by the tongue, but is drawn by rods 13 which connect with a double-tree 14 which is mounted on the frame piece 15 75 above the axle 3. The rods 13 are held in place at the front by collars or hangers 16 which engage the forward parts 6 of the sills. Swingletrees 17 are attached to the forward ends of the draft rods 13. Thus 80 the machine is drawn from the rear part.

The cutting and gathering mechanism is suspended on a rectangular frame which is supported on the sills 1 and 2. A single casting 18 forms the top of this frame. 85 Two of the posts 19 are connected by T-connections 21 and 22 to the sill 1 and two of the posts 20 are connected by T-connections 21 and 22 to sill 2. A box 23 is mounted on frame pieces 24 which have bearings 90 25 which engage the posts 19 and 20 loosely,—one piece 24 engaging the pair of posts 19 and one piece 24 engaging the pair of posts 20. The box 23 supports the gathering and cutting mechanism and driving gear for the 95 gathering and cutting mechanism and the box 23 with the gathering and cutting mechanism and the driving gear for said mechanism is vertically movable as hereinafter described. The object in having the gathering and cutting mechanism vertically movable is to adapt the machine to cut the heads from plants of various heights. For this reason the posts 19 and 20 are made high enough to give a considerable range of vertical adjustment. 100

The gathering and cutting mechanism are mounted on the box 23. The heads are cut by rotary knives 26 which lap upon each by some extent and cut somewhat as 110 scissors cut. The blades are slightly indented with curved indentations and the out-

- ward projection of one blade passes over the indentation of the other blade. These blades are mounted on vertical shafts 27. Bearings 28 are provided for the shafts 27. The 5 bearings 28 are attached to the underside of the box 23, and are carried by this box. Bevel gear wheels 29 are mounted on the lower ends of the shafts 27. Bevel gear wheels 29 are driven by bevel gear wheels 10 30 which are driven by the shaft 31. The piece of metal which forms the bearings 28 also forms the upper parts of the bearings 32 for the shaft 31. The lower parts or halves of the bearings 32 are formed integral 15 with a casting 33 which is bolted to the front of the box 23 and also to the bottom of the box 23 by means of arms 34 which extend under the box, the arms 34 being formed integral with the casting 33.
- 20 Means are provided for gathering the heads and bringing them in the path of the knives 26. Arms 35 are attached to the bearings 28 and project forwardly and outwardly, as illustrated in Fig. 1. These arms 25 carry drag belts 38 which are provided with outwardly and horizontally projecting teeth and travel as the knives are rotated. The drag belts converge as they approach the knives and thus bring the heads directly in 30 the path of the knives. Sprocket wheels 36 are mounted on the upper parts of the shafts 27. Idle sprocket wheels 37 are mounted on the arms 35 at the ends thereof and also at the bends of said arms and drag chains 38 35 are mounted on and driven by the sprocket wheels 36 and 37. The power for driving the shaft 31 is transmitted from the rear axle 3. A bevel gear wheel 39 is loosely mounted on the axle 3. The wheel 39 may 40 be locked to the axle 3 by the clutch 40, as hereinafter described. The wheel 39 drives a bevel gear wheel 41 which is mounted on a shaft 42. A bevel gear wheel 43 is mounted on the forward end of shaft 42. Gear 45 wheel 43 drives a bevel gear wheel 44. The bearings 45 are formed integral with the connections for the sill 2, the post 20 and the sill 6. The wheel 44 is mounted on the vertical shaft 46 which shaft is square in cross- 50 section. The shaft 46 drives a cog-wheel 47 through which the shaft projects loosely in order that the cog-wheel may be moved vertically on this shaft. The cog-wheel 47 is supported in a bearing 48 which is rigid 55 with the box 23, being bolted thereto. The cog 47 drives a pinion 49 which is mounted on a vertical shaft 50. The shaft 50 is also journaled in the bearing 48. A bevel gear wheel 51 is mounted on and driven by the 60 shaft 50. Gear wheel 51 drives a bevel gear wheel 52 which drives the shaft 31. This completes the description of the gearing for transmitting the power from shaft or axle 3 to the gathering and cutting mechanism.
- 65 The same power drives a traveling apron 53 which is mounted on drums 54. The drums 54 are journaled in bearings 55 which are attached to the box 23. A bevel gear wheel 56 is mounted on the shaft of one of the drums 54 and wheel 56 is driven by a gear wheel 57 70 which is driven by the shaft 31. The gear wheels 57 and 56 might be located at either end of the box 23. The belt or apron 53 has ribs 58 attached thereto. This apron delivers the heads which fall from the knives 75 26 in the box 23 to one side of the box.
- The heads that fall in the box 23 may be delivered to a dumping box 59 as shown in Fig. 2, or they be delivered to an elevator 60 for dumping the heads into a wagon, or 80 the heads might be dropped on the ground from the box as the machine moves along.
- If an elevator is used, it may be operated from either side of the box 23. The elevator consists of a traveling apron or carrier 61 85 which is mounted on the driven drum 62 and the idle drum 63 which are journaled in the frame pieces 64. The drum 62 is also journaled in bearings 65 which are attached to the box 23. The apron 61 may be driven 90 from the shaft 54. Gear wheels 66 are mounted on the shafts 54 and 62 and a belt 67 driven by the gear wheel on shaft 54 mounted on the wheels 66. The outer end of the elevator is held in operative position 95 by a cable 68 which is attached to a bail 69 near the end of the elevator and to a bail 70 attached to the box 23 and passed over a pulley 71 which is hung from the frame 18. The end of the elevator next to the wagon 100 will always remain at the same height above the wagon whether the box 23 is in a low or elevated position because when the bail 70 rises the cable 68 will run through the pulley 71 and the outer end of the elevator will remain at a constant height. 105
- If a dumping box is used it will be arranged as shown in Fig. 2. 59 represents the box. This box is pivotally mounted on pivot bolts 72 which are supported in bearing arms 73 which are attached to the box 23. The side 74 of the box 59 is rigid with the box 23, being made rigid therewith by braces 75. A cable 76 is attached to the outer part of the box 59 by an eye-screw 77 110 and run over the pulley 71 (it being understood that when the box 59 is used the elevator 60 is not used) back towards the seat 77. By pulling on the cable 76 the box 59 may be swung outwards and upwards and 115 the accumulated heads dumped on the ground. 120
- Means are provided for elevating the box 23 together with all the gathering and cutting mechanism, the box 23 carrying this 125 mechanism. The sills 24 which support the box 23 have bearings 25 which are movable vertically on the posts 19 and 20 and these frame pieces or sills 24 have bearings 25 which engage the posts loosely and are of 130

sufficient depth to make a firm support at whatever height the box may be elevated. Lugs 78 are formed on the bearings 25, as shown in detail in Fig. 6. Sprocket wheels 79 are mounted on shafts 80 which are journaled in bearings 81 which are attached to the upper parts of posts 19 and 20. Sprocket chains 82 are mounted on these sprocket wheels. These sprocket chains are not endless sprocket chains, but only long enough to elevate the box 23 to any desired height. The sprocket chains 82 are attached to rods 83 which are threaded and project through the lugs 78. Adjusting nuts 84 engage the lower ends of rods 83. Cables 85 are attached to the sprocket chains 82 and run under pulleys 86 which are mounted on the posts 19 and 20. The cables 85 are then attached to rings 87 which are mounted on the rods 83 between the lugs 78 and nuts 84. By these means the height to which the box 23 may be elevated can be regulated. The shafts 80 are driven by bevel gearing as follows. Gear wheel 88 is mounted on shaft 80. This gear wheel is driven by the gear wheel 89 which is mounted on shaft 90. Shaft 90 is mounted in bearings 91 which are attached to the posts 20. Shaft 90 drives a gear wheel 92. Gear wheel 92 drives a gear wheel 93 which is mounted on and drives the rear shaft 80 and the gearing mounted on said shaft. The gearing for elevating the rear of box 23 is the same in construction as the gearing for elevating the front of said box. The shaft 90 is driven by hand power. A bar 94 is attached to the posts 20 and extends backward and then bent to form the bearing 95 for the shaft 90. The shaft 90 is provided with a crank 96 which the operator can use from his seat. With the means thus described the operator can regulate the gathering and cutting mechanism to cut the heads from cane of any ordinary height.

Means are provided for throwing the cutting and gathering driving gear out of operation at will. This is done by throwing the clutch 40 out of mesh with the wheel clutch 97. The clutch 40 moves with the axle 3 by reason of the key 98 and this clutch is axially movable. A lever 99 is fulcrumed on the arch bar 15 and provided with a yoke 100 which engages the clutch 40 in a groove 101 therein. A rack 102 is attached to the arch 15 and the lever 99 carries a lug 103 which engages the rack 102 to hold the lever at the desired adjustment. The fulcrum bolt 104 projects forwardly and a spiral spring 105 is mounted on this bolt and serves to hold the lug 103 of the lever 99 in engagement with the rack 102. An arch bar 106 is attached to the arms 35 and braces these arms. The main function of this bar 106 is to press the head of the plants down. Some of the heads will stand up higher than others. This bar will tend to

bring all of the heads even and the heads will be engaged by the drag belts 38 as these belts move along so that the knives 26 will cut the head practically with the same amount of stalk.

Having fully described my invention, what I claim as new and desire to secure by Letters Patent, is,—

1. A heading machine comprising a wheeled carriage, blades for cutting heads of plants, drag belts projected in front of said blades for guiding heads of plants to said blades, a vertically movable receiving box carrying said blades and drag belts and holding the same in operative relation, and means actuated by said carriage for rotating said blades and driving said drag belts at any adjustment of said box.

2. A heading machine comprising a wheeled carriage, blades for cutting heads of plants, upright shafts for said blades provided with suitable bearings, drag belts projected in front of said blades, arms projecting from said bearings and provided with gearing for driving said drag belts, and means actuated by said carriage for driving said shafts.

3. A heading machine comprising a wheeled carriage, blades for cutting heads of plants, drag belts for guiding the heads of plants to said blades, arms supporting said drag belts, means carried by said arms for bending the heads of plants in line with said drag belts, and means actuated by said carriage for driving said blades and said drag belts.

4. A heading machine comprising a carriage having a rotating axle and wheels therefor supporting the rear of said carriage, an arch and wheels therefor supporting the front of said carriage, rotary blades, shafts for said blades mounted on said carriage, and gearing actuated by said rear axle for driving said blades.

5. A heading machine comprising a carriage having a rotating axle and wheels therefor supporting the rear of said carriage, an arch and wheels therefor supporting the front of said carriage, draft rods operatively connected to said rear axle and supported on the front of the carriage, rotary blades, shafts for said blades mounted on said carriage, drag belts projected in front of said blades, and gearing actuated by said rear axle for driving said blades and drag belts.

6. A heading machine comprising a wheeled carriage having a revolving axle, an upright frame mounted on said carriage, a receiving box mounted on and vertically movable on said upright frame, rotating blades carried by said box, drag belts for guiding heads of plants to said blades, gearing for driving said blades and drag belts carried by said box, and gearing actuated

by said revolving axle for driving said first named gearing at any adjustment of said box.

7. A heading machine comprising a wheeled carriage provided with a revolving axle, a receiving box, upright posts mounted on said carriage, a horizontal frame carrying said box and moving loosely on said posts, means for effecting vertical adjustment of said box on said upright posts, rotating blades carried by said box, drag belts movable vertically with said box for guiding the heads of plants to said blades, gearing carried by said box for driving said blades and drag belts, a vertical shaft for driving said blade gearing, gearing actuated by said revolving axle for driving said vertical shaft, and means for throwing the last named gearing in or out of gear with said revolving axle.

8. A heading machine comprising a wheeled carriage, a receiving box mounted on said carriage, drums and a delivery belt running on said drums carried by said box, rotating blades carried by said box, drag belts for guiding the heads of plants to said blades, manually operated gearing for vertical adjustment of said box and gearing actu-

ated by said carriage for driving said blades and said delivery belt and said drag belts, 30 said box holding said drums and delivery belt, drag belts, rotating blades; and gearing therefor in operative relation.

9. A heading machine comprising a carriage having a rear revolving axle and 35 wheels therefor, an arch and wheels supporting said arch for supporting the front of said carriage, draft rods operatively connected to said rear axle and supported on the front of the carriage, swingletrees 40 connected to the said draft rods, tongues connected to said arch and serving as guides, arms attached to the forward ends of said tongues, an arch connected to the front ends of the tongues, a receiving box mounted on 45 said carriage, blades carried by said box, and gearing actuated by said revolving axle for driving said blades.

In testimony whereof, I set my hand in the presence of two witnesses, this sixth day 50 of October, 1906.

WILLIAM M. TAYLOR.
